OIL WELL PUMP

George H. Roberts, Los Angeles, Calif., assignor
of one-half to A. E. Schulze, Los Angeles,
Calif.

Application July 1, 1931. Serial No. 548,123

5 Claims. (Cl. 103—204)

My invention relates to an oil well pump and has for its principal objects, to generally improve upon and simplify the construction of the existing form of oil well pumps, to provide a pump 5 having a reciprocating piston operating within a cylinder and which piston and cylinder are provided with cooperating means that are effective in building up pressure of the oil within the cylinder so as to eliminate the conventional pack-10 ings generally used between the piston and cylinder and at the same time providing means for increasing the pressure of the oil within the cylinder as the piston approaches the upper end of its stroke and further, to provide simple and 15 efficient means for automatically cleaning the seats of the travelling valves and maintaining the same free from accumulations of sand, mud, gravel and the like.

A further object of my invention is, to provide 20 simple and efficient means for heating the oil that enters the pump cylinder so as to materially increase the fluidity of said oil so that it will flow more readily through the pump and upwardly through the pump tube.

25 With the foregoing and other objects in view, my invention consists in certain novel features of construction and arrangement of parts that will hereinafter be more fully described and claimed and illustrated in the accompanying 30 drawings in which:

Fig. 1 is a vertical section taken lengthwise through the center of a pump constructed in accordance with my invention and showing the same in position in a well.

35 Fig. 2 is a vertical section taken lengthwise through the upper portion of the pump cylinder and showing the standing valves therein.

Fig. 3 is a horizontal section taken on the line 3—3 of Fig. 2.

40 Fig. 4 is a vertical section taken lengthwise through the central portion of the pump cylinder and showing the piston positioned therein.

Fig. 5 is an enlarged vertical section taken through the lower portion of the pump piston 45 and showing the lower one of the traveling valves.

Fig. 6 is a vertical section taken lengthwise through the lower portion of the pump cylinder and showing the oil heating means that is positioned below the strainer that is connected to 50 the lower end of the pump cylinder.

Fig. 7 is an enlarged horizontal section taken on the line 7—7 of Fig. 6.

Fig. 8 is an enlarged cross section taken on the line 8—8 of Fig. 6.

55 Referring by numerals to the accompanying

drawings which illustrate a practical embodiment of my invention, 10 designates the pump cylinder that has its upper end connected by a suitable tubular coupling 11 to the lower end of the string of tubing 12 that carries the oil to 60 the top of the well.

Removably located within the lower portion of coupling member 11 directly above the upper end of cylinder 10, is a block 13 in the center of which is formed an axial opening 14 that serves as a bearing for the piston rod 15 and formed through said block 13 to the sides of said central opening is a series of ports 16 provided at their upper ends with seats 17 for standing valves 18, the latter being preferably of the spherical type. 70

Arranged in the holes 16, above the valves 18 are cages 19 that limit the upward movement of the valves 18.

The upper end of piston rod 15 is connected in the conventional manner to the lower end of 75 the pump or sucker rod 20 and which latter extends upwardly through the tubing 12.

Detachably secured to the lower end of cylinder 10 is a standing valve housing 21, within which is formed a plurality of seats 22 for standing 80 valves 23, preferably of the spherical type and arranged within the housing 21 a short distance above each valve 23 is a cage 24.

Arranged immediately beneath each standing valve 23 and its seat is an automatically acting 85 seat cleaning member 25, the construction of which will be hereinafter more fully described.

Detachably secured to the lower end of the valve housing 21 is the upper end of a strainer tube 26^a of conventional structure and secured to the lower 90 end of this strainer tube is a block 26, through which passes the open upper end of a depending oil circulation tube 27.

Formed in block 26 to the side of tube 27 is a pair of separated chambers 28 and 29 and communicating with chamber 28 is the lower end of a steam supply pipe 20 that extends downwardly through the well from the top thereof.

Secured to the underside of block 26 is the upper end of a depending tube 32 that encloses tube 95 27 and secured to the lower end of this tube 32 is a slotted or perforated strainer cap 33.

A plug 34 is seated in the lower end of tube 32 and the lower end of the tube 27 extends through this plug 34 and communicates with the 100 chamber in the strainer cap 33.

The upper end of a steam circulation tube 35 extends lengthwise through tube 32 and the upper end of said tube 35 is seated in the block 26 and communicates with chamber 28.

The open lower end of tube 35 terminates at a point just above the plug 34 that closes the lower end of tube 32.

Seated in the lower portion of the wall of tube 32 just above the upper end of the cap 33 is a pressure outlet valve 36.

The inner portion of chamber 29 has communication with the upper end of the chamber in tube 32 by means of port 37 and seated in block 26 is the 10 lower end of a steam circulation pipe 38 that extends to the top of the well.

Arranged for reciprocatory movement within the cylinder 10 is a tubular piston 39 and a suitable coupling member 40 provided with openings 15 41 connects the upper end of this piston to the lower end of the piston rod 15.

The external diameter of the piston 39 is substantially less than the internal diameter of the cylinder 10, thereby forming an elongated annular oil circulation chamber 42 between the piston 20 and cylinder.

Secured in any suitable manner to the inner face of cylinder 10 and spaced suitable distances apart vertically thereof, are collars 43, the thickness 25 of which is approximately half the width of annular space 42 and depending from the inner portion of each collar 43 is a short sleeve 44 that is approximately half the thickness of the collar 43, thereby providing a narrow oil circulation 30 space 45 between said sleeve and the wall of cylinder 10.

Formed through the wall of each sleeve are slots or perforations 46 which are inclined so that they project upwardly and inwardly from the outer 35 surfaces of the sleeves.

Secured to piston 39 and arranged on the exterior thereof are collars 47, the thickness of which is approximately the same as the thickness of the collars 43 and depending from the outer portion 40 of the lower edge of each collar 47 is a sleeve 48 that is approximately half the thickness of the collar 47, thereby providing a narrow circulation chamber 49 between each sleeve 48 and the wall of piston 39.

Each sleeve 48 is provided with perforations or slots 48a that are inclined so that they extend upwardly and outwardly and which arrangement is just the reverse of the inclination of the slots or perforations 46 in the sleeves 44.

The external diameters of the collars 47 and sleeves 48 is slightly less than the internal diameters of the collars 43 and 44 and thus as the piston 39 reciprocates within the cylinder the collars 47 and sleeves 48 move past the collars 43 and sleeves 44 and there is very little clearance between the two seats of collars and sleeves.

The cooperating collars and sleeves just described are for the purpose of doing away with the usual mechanical packings that are ordinarily employed between a piston and cylinder and for also building up pressure of oil within the upper portion of the chamber between the cylinder and piston.

The lower end of sleeve 44 is bevelled from its outer edge upwardly and inwardly and the lower end of sleeve 48 is bevelled from its inner edge inwardly and outwardly. The lower end of the wall of the piston 39 is bevelled from its outer edge upwardly and inwardly.

Removably seated in the lower portion of piston 39 is a ring block 50 provided in its upper portion with a seat 51 for a travelling valve 52 and which latter is preferably in the form of a sphere.

Arranged within the piston 39 immediately

above block 50 is a cage 53 that limits the upward movement of valve 52.

Arranged to reciprocate freely through the port in ring 50 is a valve seat cleaning member comprising a tubular body 54, the external diameter of which is slightly less than the diameter of the port through ring 50 and the lower portion of the tubular body 54 is enlarged in diameter and this enlarged lower end normally rests on lugs 55 that project inwardly from the lower portion of a bushing 56 that is removably seated in the lower end of a piston 39 directly below ring 50.

The enlarged lower portion of the tubular body 54 is provided with a circumferential inclined face 57, that is adapted to engage against the inclined under faces of stop lugs 59, which latter project downwardly from the lower portion of ring 50 around the opening therethrough.

The upper end of the wall of tubular member 54 is bevelled so as to provide a sharp edge 60 which when the tubular body 54 and valve 52 are at their lower limits of movement, occupies a position just below and immediately adjacent to the seat 51 for said valve 52.

Formed on the interior of tubular member 54 just below the bevelled upper edge thereof is a downwardly and inwardly projecting inclined flange 61 and formed through the wall of said member 54 directly beneath this flange is a plurality of apertures 62.

A travelling valve 63 normally closes the port through a ring 64 that is located within the upper portion of the piston 39 and disposed above said valve is a cage 65 and arranged for reciprocatory movement through the port in the ring 64 is a 100 tubular valve seat cleaning member 66.

The parts 63, 64, 65 and 66 are identical in construction and operation with the parts 52, 50, 53 and 54 heretofore described and likewise the parts 23, 24 and 25 that occupy the valve housing 21 are identical in construction and operation with said parts 52, 53 and 54.

During operation of my improved pump piston 39 is reciprocated within the cylinder or barrel 10 and the oil that is elevated by the pump passes 120 through the strainer 26 and as the standing valves 23 are drawn upwardly during the suction or upward stroke of the pump piston this oil enters pump cylinder 10. A certain amount of oil enters strainer 33 and passes upwardly through tube 27 into the lower portion of the strainer 26a and if during pumping operations, relatively heavy oil is encountered or oil that will not flow readily, such oil may be softened by the heat of steam that is forced downwardly through tube 125 30 and which steam after passing through chamber 28 passes downwardly through tube 35 and discharges into the lower portion of the chamber within tube 32 and after circulating upwardly through this chamber around oil circulation tube 130 27 this steam passes through port 37 and the chamber 29 and from thence said steam exhausts upwardly through pipe 38. This circulation of steam through the chamber within the tubular housing 32 is highly effective in heating the oil 140 that passes through circulation tube 27 and consequently increasing the mobility of said oil.

On the downward stroke of the pump piston the standing valves 18 and 23 rest upon their respective seats while the traveling valves 52 and 63 145 are lifted from their seats by the upward pressure of the oil beneath said valves so that they move upward against their retaining cages and simultaneously the valve seat cleaning members 54 and 66 are moved upwardly until the inclined 150

shoulders 57 engage against stop lugs 59 and in thus moving upwardly the bevelled upper edges 60 of the tubular bodies 54 of the valve cleaning members move past the seats for the traveling valves, thereby cutting away any accumulations of sand, mud or the like which would otherwise prevent the traveling valves from properly seating on the succeeding upward stroke of the piston.

10 When the shoulder 57 engages the stop lugs 59, the openings 62 are positioned directly opposite the valve seats 51 and the pressure of the oil flow upwardly through openings 62 is effective in carrying off any accumulations that may have lodged on the valve seats during the previous upward movement of the piston.

Thus the valve cleaning members 54, 66 and 25 function to automatically clean the seats for the valves that are positioned directly above said cleaning members.

As the pump piston moves downwardly oil will flow upwardly past the lower traveling valve 52 and simultaneously oil will flow upwardly past the upper traveling valve 63 and the oil will discharge through openings 41 into the chamber within the cylinder or barrel 19.

During the downward movement of the piston, oil that enters the annular chambers 49 between the sleeves 48 and the piston will discharge upwardly and outwardly through the inclined openings in said sleeves 48.

At the beginning of the upward stroke of the piston the traveling valves 62 and 63 will close upon their seats and the automatic valve seat cleaning members 54 and 66 will return to their lowermost positions and as the piston moves upwardly standing valves 23 will be lifted from their seats to permit oil to flow from the strainer 26 upwardly into the cylinder or barrel 10 and simultaneously the standing valves 18 will be lifted from their seats by the oil that is forced upwardly through the barrel by the upwardly moving piston.

During this upward travel of the piston the shoulders formed by upper ends of the collars 47 will exert upward pressure on the oil within those portions of the chamber 42 that are immediately above said shoulders and below the immediately adjacent collar 43 and perforated sleeve 44 and such action materially increases the pressure upon the oil in the upper portion of the barrel. This pressure increases proportionately as the piston approaches the upper end of its stroke owing to the displacement produced by the upwardly moving piston within the chamber 42 and as a result the oil under high pressure in the upper portion of the barrel will flow past the standing valves 18 and enter the pump tube 12 which leads to the top of the well.

60 During the upward movement of the piston, it will be understood that the upper ends of the collars 47 function as pistons to travel through those portions of the chamber 42 that are immediately below the fixed collars 43 and their depending perforated sleeves 44 and that the oil forced into the annular chambers behind the sleeves 44 is restricted from escaping therefrom through the apertures 46, thereby developing increased resistance as the piston approaches the upper portion of the pump barrel.

During the upward stroke of the piston a certain amount of oil will flow downwardly through the inclined openings in the sleeves 48 and a certain amount of oil under pressure within the annular chambers 45 will flow upwardly through the

inclined openings 46 in the sleeves 44 and such action provides a fluid packing between the piston and the pump barrel and consequently eliminates the use of the conventional pump packings and which latter it will be understood wear very rapidly as a result of the action of sand and sediment contained in the oil.

The standing valves 23 in the valve housing 21 will be drawn upwardly off their seats as the piston moves upwardly within its cylinder, thereby permitting oil to be drawn by suction past said valves 23 into the cylinder 10 and as this oil flows through the openings in the members 25 the seats 22 for said valves will be automatically cleaned. At the beginning of the downward stroke of the piston valves 23 will return to their seats and tubular members 25 will move downward until they engage their respective supports.

Pressure outlet valve 36 is of the type that automatically opens under a predetermined degree of pressure, thus permitting the pressure within the cylinder 32 to blow off in the event that said pressure exceeds the predetermined degree.

Thus it will be seen that I have provided a reciprocating pump particularly designed for the pumping of oil from oil wells, which pump is constructed so that the requirement for the conventional packings between the piston and pump cylinder or barrel is eliminated and said pump being provided with cooperating means for materially increasing the pressure upon the oil as the piston approaches its upward limit of movement and said pump being provided with automatically acting means for cleaning the seats that are occupied by the standing and traveling valves and consequently materially increasing the efficiency of the pump and the life or effective period of service thereof.

It will be understood that minor changes in the size, form and construction of the various parts of my improved oil well pump may be made and substituted for those herein shown and described without departing from the spirit of my invention, the scope of which is set forth in the appended claims.

I claim as my invention:

1. In a pump, a cylinder, a piston arranged for operation within said cylinder, a plurality of sleeves secured to said cylinder on the interior thereof, portions of which sleeves are spaced apart from the walls of the cylinder, a piston arranged for operation within said cylinder, sleeves secured to the exterior of said piston and portions of which sleeves are spaced apart from the wall of said piston with the sleeves of both sets provided with inclined openings.

2. In a pump, a cylinder, a piston arranged for operation within said cylinder, a plurality of sleeves secured to said cylinder on the interior thereof, portions of which sleeves are spaced apart from the walls of the cylinder, a piston arranged for operation within said cylinder, sleeves secured to the exterior of said piston and portions of which sleeves are spaced apart from the wall of said piston with the sleeves of both sets provided with inclined openings and the openings in the sleeves on the piston being oppositely inclined relative to the openings in the sleeves on the cylinder.

3. In a pump, a cylinder, a plurality of collars arranged on the interior of said cylinder, sleeves depending from said collars, which sleeves are spaced apart from the inner surface of the cylinder wall, a piston arranged for reciprocatory

movement within the cylinder, collars secured on the periphery of said piston and sleeves depending from the collars on said piston, which last mentioned sleeves are spaced apart from the surface of the piston.

4. A pump as set forth in claim 3 and the members of both sets of sleeves provided with inclined openings.
